CLAIM

The ornamental design for mid span wire spacer or similar article, as shown and described.

DESCRIPTION

FIG. 1 is a front elevational view of a mid span wire spacer or similar article showing my new design, the rear elevational view being a mirror image.

FIG. 2 is a top plan view thereof, the bottom view being a mirror image; and

FIG. 3 is a side elevational view thereof, the opposite side being a mirror image.

FIG. 1

*FIG. 2**FIG. 3*
